Louis Trecek, Madison, Wis., assignor to The Celon Company, Madison, Wis., a corporation of Wisconsin

Application March 29, 1944, Serial No. 113,069

Term of patent 14 years

(Cl. D9—2)

To all whom it may concern:

Be it known that I, Louis Trecek, a citizen of the United States, residing at Madison, Dane County, Wisconsin, have invented a new, original, and ornamental Design for a Combined Toothbrush and Holder, of which the following is a specification, reference being had to the accompanying drawing, forming a part thereof.

Fig. 1 is a rear elevational view of a combined toothbrush and holder showing my new design, Fig. 2 is a side elevational view thereof, and Fig. 3 is a top plan view thereof.

I claim:

The ornamental design for a combined toothbrush and holder, as shown.

LOUIS TRECEK.
